(57) **CLAIM**

The ornamental design for a combined headband, bows and container, as shown and described.

DESCRIPTION

FIG. 1 is an exploded top perspective view of the combined headband, bows and container showing my new design with the headband in a flattened position;

FIG. 2 is a front elevation of the head band in an expanded position, the headband is shown separately for clarity of disclosure;

FIG. 3 is a side elevation of FIG. 2, the opposite side elevation is a mirror image thereof; and,

FIG. 4 is a bottom plan view of FIG. 4.
